(57) **CLAIM**

We claim the ornamental design for a handrail, as shown and described.

DESCRIPTION

This application is a divisional reissue of U.S. application Ser. No. 29/515,597 filed Jan. 23, 2015 which is a broadening reissue of U.S. Pat. No. D706,451 which issued Jun. 3, 2014 from application Ser. No. 29/462,252 filed Jul. 31, 2013.

This application is a broadening reissue of U.S. Pat. No. D706,451 which issued Jun. 3, 2014 from application Ser. No. 29/462,252 filed Jul. 31, 2013.

FIG. 1 is a perspective view of a handrail.]

FIG. 2 is a front elevation view of the handrail of FIG. 1. The opposing rear elevation view is a mirror image of the illustrated view.]

FIG. 3 is a top plan view of the handrail of FIG. 1.]

FIG. 4 is a bottom plan view of the handrail of FIG. 1.]

FIG. 5 is a left side elevation view of the handrail of FIG. 1; and.]

FIG. 6 is a right side elevation view of the handrail of FIG. 1.]

FIG. 7 is a perspective view of a handrail;

FIG. 8 is a front elevation view of the handrail of FIG. 7, the rear elevation view is a mirror image thereof;

FIG. 9 is a top plan view of the handrail of FIG. 7;

FIG. 10 is a bottom plan view of the handrail of FIG. 7;

FIG. 11 is a left side elevation view of the handrail of FIG. 7; and,

FIG. 12 is a right side elevation view of the handrail of FIG. 7.

(Continued)

[In FIGS. 1-6, the] The broken lines [indicate environmental features and] in the drawings illustrate portions of the handrail that form no part of the claimed design.

1 Claim, 2 Drawing Sheets

Matter enclosed in heavy brackets [ ] appears in the original patent but forms no part of this reissue; matter printed in italics indicates the additions made by reissue.
